US0D1040481S

(12) **United States Design Patent** (10) Patent No.: **US D1,040,481 S**
(45) Date of Patent: ** Sep. 3, 2024

(54) **BABY BIB**

(71) Applicant: **Konny By Erin, Inc.**, Seoul (KR)

(72) Inventor: **E Rang Lim**, Seoul (KR)

(**) Term: **15 Years**

(21) Appl. No.: **35/518,174**

(22) Filed: **Mar. 22, 2023**

(80) **Hague Agreement Data**

Int. Filing Date: **Mar. 22, 2023**

Int. Reg. No.: **DM/230923**

Int. Reg. Date: **Mar. 22, 2023**

Int. Reg. Pub. Date: **Aug. 25, 2023**

(30) **Foreign Application Priority Data**

Sep. 23, 2022 (KR) 30-2022-0039048

(51) **LOC (14) Cl.** **02-02**

(52) **U.S. Cl.**
